JOHN S. HUNTER, OF HARTFORD, CONNECTICUT.

Letters Patent No. 65,085, dated May 28, 1867.

IMPROVED MOSQUITO-BAR.

The Schedule referred to in these Letters Patent and making part of the same.

TO ALL WHOM IT MAY CONCERN:

Be it known that I, JOHN S. HUNTER, of Hartford, in the county of Hartford, and State of Connecticut, have invented a new improvement in Mosquito-Bar; and I do hereby declare the following, when taken in connection with the accompanying drawings and the letters of reference marked thereon, to be a full, clear, and exact description of the same, and which said drawings constitute part of this specification, and represent, in—

Figure 1, a side view, with the bar extended.

Figure 2 the bar opened; and in

Figure 3 a front view of the bar open, showing a transverse section of the bedstead.

This invention consists in the arrangement of several bows adjustably attached to the bedstead so as to be extended, and close the bar or open and contract the bar; and in order to the better understanding of my invention, as well as to enable others to construct the same, I will proceed to a description, as illustrated in the accompanying drawings.

A are the sides of a bedstead of common construction. B B B are three bows (may be more or less in number) curved so as to extend over the bedstead, and all pivoted together at each end in a socket, C, which said socket is formed so as to set on over the edge of the bedstead sides A, and be secured thereto by means of a set-screw, or otherwise, so as to be readily removed or adjusted to different positions on the side as occasion may require. If preferred the bows may be made so as to fold for the convenience of transportation. The bows I prefer to make from light metallic or wood rods, and extending upward so as to give sufficient height above the pillows for the comfort of the occupant. Over the several bows B I place a netting of any suitable material, leaving so much to project over the front bow as will fall down upon and conform to any unevenness of the bed. When not required for use, the bows are easily detached from the bedstead or applied thereto when required, and are opened, as in fig. 3, or closed, as in fig. 1, by simply raising or lowering the bows.

Having thus fully described my invention, what I claim as new and useful, and desire to secure by Letters Patent, is—

The arrangement of the bows B, more or less in number, and combined with an adjustable socket, C, so as to be attached to the bedstead, and to operate substantially as set forth.

J. S. HUNTER.
